UNITED STATES PATENT OFFICE.

EDUARD HEBERLEIN, OF WATTWIL, SWITZERLAND.

MACHINE FOR MERCERIZING.

SPECIFICATION forming part of Letters Patent No. 624,800, dated May 9, 1899.

Application filed February 3, 1899. Serial No. 704,413. (No model.)

To all whom it may concern:

Be it known that I, EDUARD HEBERLEIN, chemist, a citizen of the Swiss Republic, and a resident of Wattwil, canton of St. Gall, Switzerland, have invented a machine for uniformly impregnating threads or yarns of animal or vegetable fibers with caustic liquids, of which the following is a clear and complete specification.

10 This invention relates to a machine for impregnating yarns or threads with caustic liquids in a perfectly uniform manner and in such a way that the operatives are not in any way liable to the danger of coming in contact 15 with the caustic liquid.

The said machine is shown on the accompanying drawings, in which—

Figure 1 shows a front view, and Fig. 2 a side view, of the same when not in use, while 20 Fig. 3 shows a side view of the same when in use for impregnating yarns or threads with lye.

The machine has at bottom a rectangular frame A, on which are fixed bearing-brackets a for carrying two shafts B. On these shafts 25 are fixed arms b, carrying the four wheels C, which support the entire machine on rails c, on which it can consequently be run along. On both sides of the frame A there are two upright supports D D' D', of which D D 30 are fixed to the frame A, while the others, D' D', are connected thereto by hinges, so that they can be turned down into a horizontal position. The fixed supports D D are stayed on the frame A by means of stays E and are 35 fixed together at top by means of a transverse beam F of trough-section. The other two supports D' D' when in the vertical position are also engaged by their upper ends with the cross-beam F, which serves for their secure 40 support. For this purpose each of the supports D' has at its upper end a metal plate e, which can be pressed against the cross-beam F, so as to hold D' in its vertical position by means of a pivoted latch H, taking into a 45 hasp m, fixed to the beam F.

On the frame A are fixed bearings f, open at top, which receive the end trunnions h of a roller I, and on the supports D' are lateral projections g, which in the vertical position 50 of the supports engage over the trunnions h, so as to prevent any vertical motion of the roller I. Above the latter is a second roller

I', the end trunnions h' of which rest in the hook-shaped ends i of two internally-threaded slides K, through which are screwed two screw-spindles L, so that by the rotation of the latter the slides will be moved upward or downward between the supports D D'. The screw-spindles project up above the beam F and carry bevel-pinions k, gearing with other 60 bevel-pinions o, fixed on a traverse shaft M, carried in bearings n on the beam F, so that on rotating the shaft M by means of a hand-wheel N the two screw-spindles are simultaneously rotated for raising or lowering the 65 slides K and roller I'.

On the shafts B are fixed hand-levers P, that can be turned through ninety degrees, so that by turning the levers from the position shown in Fig. 2 into that shown in Fig. 3 the arms 70 b, fixed on the shafts B and that carry the wheels C, are turned from the vertical position at Figs. 1 and 2 into the horizontal position, Fig. 3, and thus effect the lowering of the frame A and parts carried thereby. 75

Between the rails c c is arranged a tank S, containing the lye with which the yarns or threads are to be treated.

The machine is operated as follows: The yarns or threads x to be treated are laid over 80 the rollers I I' in a spread-out condition while the machine is in the raised position, the supports D' having been previously turned down (the latches H being raised for this purpose, as indicated by the arrows y) and the rollers 85 lifted out of their bearings for the above purpose. The yarns being laid on as described, the rollers are again placed in their bearings f and i and the supports D' are raised into their vertical position and secured by turning the latches H so as to engage with the hasps m. The shaft M is then turned, so as to rotate the screw-spindles in the direction for raising the slides K and roller I'. The roller I being prevented from rising by the 90 projections g on the supports D', the hanks of yarn will be stretched to any required degree between the rollers I I'. The hand-levers P are then turned into the position at Fig. 3, so as to lower the machine, when the under side of the lower roller I will become 95 immersed in the lye in the tank S. Upon now imparting rotation to the roller I' on fitting a crank-handle on the square end of one

of the trunnions h' or by means of any other suitable driving-gear the hanks of yarn will be made to travel around on the rollers, so as to be immersed in and become impregnated by the lye. After this has been sufficiently effected the machine is raised again by turning back the hand-levers P , the supports D' are lowered again, and the rollers I I' , together with the yarns thereon, are removed or the machine is run to a washing device for washing the yarns.

The above-described machine possesses the following advantages:

First. The machine affords the operatives perfect security against injury by the caustic lyes and renders the expensive and inconvenient working with caoutchouc gloves unnecessary.

Second. It enables a perfectly uniform impregnation to be effected, as the yarns are made to pass through the liquid in a uniformly spread-out condition.

Third. By means of the adjustable upper roller I' yarn hanks of any size can be treated by the machine.

Fourth. When using such lyes that produce a shrinking of the fibers, the fixed position of the rollers I I' after adjustment will prevent any such shrinking.

Fifth. If the yarns are to be washed after the impregnation, this can be effected without removing them from the machine by running the machine to a washing or rinsing apparatus, where the yarns can be washed while on the machine.

What I claim is—

1. A machine for uniformly impregnating yarns or threads of vegetable or animal fiber with caustic liquids, consisting of two rollers removably mounted one above the other on the framing of the machine, on which rollers the yarn or thread hanks are mounted, the lower roller being held in its bearings so as to be prevented from rising, while the upper roller is adjustable in a vertical direction for stretching the yarns, and means for raising and lowering the machine so that when in the lowered position the lower roller with the yarn upon it dips into caustic liquid contained in a tank below, so that on rotating one of the rollers the yarn thereon is made to travel through and become impregnated with the liquid while in a stretched condition, substantially as and for the purposes described.

2. A machine for uniformly impregnating yarns or threads of animal or vegetable fiber with caustic liquid consisting of two rollers

removably mounted one above the other on the framing of the machine, on which rollers the yarn or thread hanks are mounted, the lower roller being held in its bearings so as to be prevented from rising, while the upper roller is adjustable in a vertical direction for stretching the yarns, the framing of the machine being supported on wheels carried by arms that are pivotally connected to the framing and can be turned from a more or less vertical position into a horizontal position so as to lower the machine and thereby cause the lower roller with the yarn thereon to dip into a tank containing the caustic liquid, while when the said arms are turned into the vertical position the lower roller and yarn are raised out of the liquid, substantially as described.

3. A machine for uniformly impregnating yarns and threads with caustic liquid consisting of two rollers removably mounted one above the other on the framing of the machine, on which rollers the yarn or thread hanks are mounted, the upper roller having its trunnions carried in vertically-adjustable hooks, while the trunnions of the lower roller are carried in bearings open at top in which they are prevented from rising by projections on vertical supports that can be turned down on pivots and are secured in the vertical position by locking-latches, a tank for containing the caustic liquid situated below the lower roller of the machine, and means for raising and lowering the machine so that the lower roller shall either dip into the liquid in the tank, or shall be raised out of it, substantially as described.

4. In a machine for impregnating yarns, the combination with the base-frame and the upright frame thereon, of the roller I , mounted rotatively in the base of said upright frame, the vertically-adjustable roller I' , mounted also in said upright frame, and the means for raising and lowering said frames, said means comprising the levers P , shafts B , arms b , on the said shafts, respectively, and substantially at right angles to the levers P , and the wheels C , carried by said arms, substantially as set forth.

In witness whereof I have hereunto signed my name in the presence of two subscribing witnesses.

EDUARD HEBERLEIN.
